FIG. 1

FIG. 5

FIG. 1 is a perspective view of a filter for home aquariums showing my new design.

FIG. 2 is an elevational view taken from one side thereof, the opposite side being a mirror image of the side shown.

FIG. 3 is a rear view thereof.

FIG. 4 is a top plan view thereof.

FIG. 5 is a bottom view thereof.

Both side views are identical.

The fragmentary broken line representation of an aquarium in FIG. 1 is for purposes of illustration only.

I claim:

The ornamental design for a filter for home aquariums, as shown and described.
